Edgar Gash

UNITED STATES PATENT OFFICE.

EDGAR GASH, OF MACOMB, ASSIGNOR OF ONE-HALF TO BENJAMIN B. DURFEE, OF PEORIA, ILLINOIS.

STOVE-PIPE LOCK.

SPECIFICATION forming part of Letters Patent No. 403,425, dated May 14, 1889.

Application filed January 2, 1889. Serial No. 295,187. (No model.)

To all whom it may concern:

Be it known that I, EDGAR GASH, a citizen of the United States, and a resident of Macomb, in the county of McDonough and State 5 of Illinois, have invented a new and useful Improvement in Stove-Pipe Locks, of which the following is a specification, which will enable others skilled in the art to make and use the same, reference being had to the accompanying drawings, and to the letters of reference marked thereon.

The object of this invention is to construct a simple device for locking and holding a stove-pipe firmly to a brick or other constructed flue; and its novelty consists in a device where the locking-bar can be adjusted to different lengths, so that it can be attached to flues of different thicknesses, all of which will be fully set forth in the following description, and pointed out in the claim.

In the drawings, Figure 1 is an elevation, partly in section, showing the manner in which the lock secures the pipe to the flue. Fig. 2 shows the locking-bar in perspective. 25 Fig. 3 shows the clamping-bolt detached.

In the drawings, A represents the stove-pipe, a part being cut away to show the manner of locking the pipe in the flue B. The lock-bar c is constructed as shown in Fig. 2, the front 30 end being bent up to form an inside stop, t, the rear end being enlarged, so as to admit the slot a. On one side of this slot a are formed teeth d. The clamping-bolt n (shown in Fig. 3) is threaded nearly its whole length 35 and has attached to its head a small toothed wheel, i. The teeth in this wheel i are of the same pitch as the teeth d in the slot a in the lock-bar c, which arrangement is for the purpose of adjusting the lock-bar c to different 40 lengths, as may be required. The upper end of this bolt n is flattened, so that it can be turned with thumb and finger or held while the thumb-nut s is turned either up or down.

The operation is as follows: At the proper distance from the end of the pipe A, that passes 45 into the flue B, a hole is made large enough to allow the bolt n to pass through after the thumb-nut s is taken off. The lock-bar c is then placed in the pipe A, and the bolt n is passed through the slot a in the lock-bar and 50 through the hole described in the pipe. The thumb-nut s is then placed on the bolt and screwed down sufficient to raise up the inside stop, t, level with the end of the pipe. Then the pipe is inserted into the flue B. The lock-bar c is then adjusted to the proper length 55 as follows: The teeth on the side of the slot a in the lock-bar and the teeth in the wheel i on the head of the bolt n mesh together, and by turning the bolt n the lock-bar, by means 60 of the toothed gear, can be slid in or out, as desired, until the lock-bar c is in the required position, the inside stop, t, being up firm against the inside of the flue B. The nut s is then turned down until it is tight, which 65 clamps the pipe and lock-bar together and holds the same firmly in the flue. (See Fig. 1.)

Having thus described my invention, what I claim as new, and desire to secure by Letters Patent, is—

In combination with a stove-pipe, a locking device consisting of a bar, c, having a slot, a, cut so as to form the teeth d, for the purpose of adjustment, and the inner end being bent up at right angles to form an inside stop, t, 75 and the stay-bolt n, having thumb-nut s, and a toothed wheel, i, formed on the head for adjusting the bar c and securing it firmly to the stove-pipe, substantially as shown and described.

EDGAR GASH.
